TONE CONTROL FOR HIGH OR LOW TONES
IN ELECTRICAL MUSICAL INSTRUMENTSWinston E. Kock, Cincinnati, Ohio, assignor to
The Baldwin Company, Cincinnati, Ohio

Application September 27, 1935, Serial No. 42,486

5 Claims. (Cl. 84—1)

My invention relates to that type of musical instrument in which the tones are generated by electrical means, amplified and sent out as sound through a loudspeaker.

5 In my application #701,173, filed December 6, 1933, I show a means for producing music by the use of a glow discharge circuit. In that particular circuit any number of tones may be played at the same time, the same as on a pipe organ or 10 reed organ and in that circuit all notes would be of the same loudness, which would be controlled together by a swell pedal.

15 In the present invention I propose to add certain circuits whereby the highest note played on the scale can be made to sound louder than the rest, and since in hymns the highest note of a chord is generally the melody note the melody is thus made to stand out clearly.

20 Another object of my invention is to enable a player to couple in a circuit so that the 16 ft. register would play on the lowest note of a chord. This is desirable for organists who prefer not to use the pedal keyboard.

25 In the drawing Fig. 1 is a circuit of a monophonic control for the highest note of a chord.

Fig. 2 is a circuit which would sound only the 30 lowest note of a chord.

Fig. 3 shows the use of the invention in an electric organ of the type using an inductive glow oscillator.

Figs. 4 and 5 show the use of the invention in an electric organ using any type of tone generator.

In an electric organ of the type shown in my co-pending application, #701,173, filed December 35 6, 1933, the tones are generated electrically and are connected in parallel so that no matter how many notes are played at once they will all sound, but the intensity of all notes will be equal. In most organ music the high note is the melody 40 note and should be slightly louder or it may be that a different tone timbre is desired for this note, so I have employed another circuit, controlled by a different set of contacts, so arranged that only the note corresponding to the highest 45 key depressed is transmitted to an amplifier. This amplifier can be adjusted to impart a different tone timbre or increased volume to this particular note. It is also desirable to couple in the deep bass notes and accentuate them; this 50 can be done by another similar set of contacts by means of which only the lowest note played would sound.

In order to more fully understand my invention, I have shown a monophonic circuit with two 55 keys and circuits in Fig. 1. The tone generators

would consist of a glow tube G whose oscillations are controlled by resistances R₂ and R₃ and condensers C₁ and C₂ for one note or resistances R₂, R₃ and R₄ and condenser C₂ for another note. No matter how many notes are in series the circuit would be kept from oscillating by resistance R₁, when all contacts are closed. R₂ is a resistance set to regulate the voltage from the source of current B. A set of keys or contacts K and K₁ are normally kept closed, but if key K is opened 10 the circuit comprising the resistances R₂ and R₃, condensers C₁ and C₂ and the inductance L will be associated with the glow lamp G, causing it to oscillate at the frequency corresponding to the note represented by key K, and this frequency is 15 sent to the amplifier. If, on the other hand, key K is opened the circuit consisting of R₂, R₃, R₄, C₂ and L will be associated with the glow lamp, which will then oscillate at the frequency of the note corresponding to the key K₁. 20

If it is found desirable to bring out a bass note more strongly, a circuit like that shown in Fig. 2 is used, consisting of a source of current DC, controlling resistance R₅, a glow tube G₁, an inductance L₁, condensers C₃ and C₄ and C₅, and 25 key K₂, K₃ and K₄. When these keys are closed the circuit is not in oscillation, but upon opening key K₂ the circuit would be set into oscillation by the association of the glow tube G₁, condenser C₃ and the inductance L₁. The opening of either K₃ 30 or K₄ would have no effect on the circuit. In this way only the lowest note would pass thru to the amplifier.

Fig. 3 shows the use of a monophonic instrument in combination with a polyphonic instrument. G₂ is a glow lamp operating at a frequency determined by the resistances R₆, R₇, R₈ and the condenser C₆, and furnishes the oscillations to fortify the topmost note of the chord played on the polyphonic instrument. G₃, G₄ 40 and G₅ are glow lamps of the main oscillators of the polyphonic instrument. Switches S₁ and S₄ are affixed to the key representing the generator of G₃, switches S₂ and S₅ to the key representing the generator of G₄, and switches S₃ and S₆ to 45 the key representing generator G₅. When the key corresponding to generator G₃ is depressed, switches S₁ and S₄ are closed and a small stabilizing voltage from generator G₃ is fed through condenser C₇ to oscillator G₂. The closing of S₁ 50 also connects the generator G₂ to the D. C. voltage supply B through resistances R₆, R₇ and R₈ causing it to oscillate at the proper frequency. The small stabilizing voltage through C₇ holds the oscillations of G₂ in tune with the accurately 55

pitched oscillations of G_3 . The oscillations from G_2 can be sent to a special amplifier to produce any desired intensity or tone color. For example in Fig. 3 the oscillations from G_2 are sent to the 5 terminals H of the amplifier where they can be filtered or amplified before combining with the oscillations of the main generators, which oscillations are sent to terminals J of its own amplifier or filter device as shown. The switching 10 arrangement is such that only that frequency corresponding to the topmost note of the chord played is fed to the monophonic oscillator, and this oscillator is in turn connected to the voltage supply B through that amount of resistance 15 which will cause it to oscillate at that particular frequency.

In Fig. 4 is shown a monophonic system employing any kind of a tone generator, such as, toothed wheels and magnetic pick-up, vibrating 20 reeds or strings or photo cell pick-up. The key contacts S_{10} , S_{11} and S_{12} are made to control the output of the generators T_1 , T_2 and T_3 so that the highest note only will sound.

In Fig. 5 the order is reversed from Fig. 4 so 25 that key contacts, S_7 , S_8 and S_9 will control the output of the tone generators T_4 , T_5 and T_6 so that only the lowest note will sound.

Modifications may be made in the generation 30 of tones but what I claim as my invention is:

30 1. In an electrical musical instrument, a plurality of oscillation generators, an amplifying system and a sound producing device, means for selectively connecting said oscillation generators to said amplifying system and sound producing 35 device, an additional oscillation generator, means for causing said additional oscillation generator to oscillate at the frequency of one of the generators connected to said amplifying system, and means for separately varying the intensity and tone color of the oscillations produced by said 40 additional generator.

40 2. In an electrical musical instrument, a plurality of oscillation generators, an amplifying system and a sound producing device, means for selectively connecting said oscillation generators to said amplifying system and sound producing 45 device, an additional oscillation generator com-

prising a glow discharge tube oscillator, contact means connected to the first named oscillation generators, the contact means so arranged that only one of the first named oscillation generators will influence the additional oscillation generator 5 at the same time.

3. In an electrical musical instrument, a plurality of switch controlled tone generators, another tone generator adapted to oscillate at different frequencies, contact means controlled by the first named switches to set the second generator into oscillation at a frequency of one of the first named generators.

4. In an electrical musical instrument, a plurality of oscillation generators comprising one 15 for each note of a range of notes to be reproduced, an amplifying system and a sound producing device, means for selectively connecting said oscillation generators to said amplifying system and sound producing device, an additional oscillation 20 generator capable of producing selectively notes of said range, contact means connected to the first named oscillation generators and to said second named oscillation generators, said contact means so arranged that only one of said 25 first named oscillation generators will influence said second named oscillation generator at the same time, and electrical means for causing said second named oscillation generator to oscillate at the frequency of that one of said first mentioned oscillators which influences it.

5. In an electrical musical instrument of the poly-phonic class, poly-phonic tone generating means comprising an oscillation generator for each note of a desired range and means in said 35 instrument for producing also a mono-phonic solo or accompaniment effect comprising a series of connections from said poly-phonic means, an amplifier, a loud speaker, said connections serving 40 to transmit to said amplifier oscillations produced by said poly-phonic means, and means in said connections for confining the oscillations so transmitted to oscillations corresponding to a selected one of said connections simultaneously 45 actuated.
